(57) CLAIM

The ornamental design for a yoga mat, as shown and described.

DESCRIPTION

FIG. 1 is a front, right perspective view of a yoga mat, according to an embodiment of the design.

FIG. 2 is a front view of the yoga mat, according to the embodiment of the design.

FIG. 3 is a rear view of the yoga mat, according to the embodiment of the design.

FIG. 4 is a right side view of the yoga mat, according to the embodiment of the design.

FIG. 5 is a left side view of the yoga mat, according to the embodiment of the design.

FIG. 6 is a top view of the yoga mat, according to the embodiment of the design; and,

FIG. 7 is a bottom view of the yoga mat, according to the embodiment of the design.

The broken lines shown in the figure drawings are included for the purpose of illustrating environment and form no part of the claimed design.

1 Claim, 5 Drawing Sheets
